TEMPORARY BINDER

Filed Jan. 30, 1926

UNITED STATES PATENT OFFICE.

GEORGE H. MOORE, OF BOSTON, MASSACHUSETTS.

TEMPORARY BINDER.

Application filed January 30, 1926. Serial No. 84,892.

This invention relates to a loose-leaf binder of the type disclosed by my Patent No. 1,441,873, dated January 9, 1923, and comprising a base provided at one edge portion 5 with bearings and guiding slots, a plurality of leaf-engaging members including resilient arched portions and axle portions joined to the inner ends of the arched portions and journaled in said bearings, each arched portion 10 extending through a guiding slot and having a notch adjacent its outer end, and a plurality of orifices in the base, each forming a detent adapted to be engaged by the notch of one of the arched portions, when 15 the latter is turned about the axis of its axle portion into operative position.

In said binder the bearings, the guiding slots, and the detent-forming orifices are formed in a sheet-metal member constituting 20 an element of the base. The flexibility of said member, due to the inherent flexibility of the sheet metal, and to the weakening thereof by the formation of the guiding slots and detent orifices therein, is such that the member may 25 be easily bent crosswise, and thus distorted from its predetermined and essential straight form. It is therefore necessary to provide means for stiffening the sheet-metal member, and this is accomplished in the device of 30 said patent, by stiffening means incorporated in the back of the cover, so that the complete binder necessarily includes a cover, the back of which is structurally stiffened.

The chief object of the invention is to provide 35 an improved base formed independently of the cover and including a sheet metal base member provided with the guiding slots and detent orifices, and a reinforcing member co-operating with the sheet-metal member and 40 in forming, in one edge portion of the base, a cavity in which the axle portions are journaled, and, in the opposite edge portion of the base, a cavity adapted to receive the notched 45 ends of the leaf-engaging members, the base and leaf engaging members being adapted for attachment as a unit to the cover back, which is limp and flexible, so that the cover may include 50 a back and sides formed from a single sheet of flexible material, as leather, paper, or cloth, the desired stiffness being provided wholly by the independently formed base.

Another object is to provide a base characterized as above stated, in which the sheet-metal member bottoms the cavity receiving

the notched ends of the leaf-engaging members and prevents said ends from indenting and wearing the cover back.

I attain these and other related objects by the improved base construction herein-after described and claimed.

Of the accompanying drawings forming a part of this specification—

Figure 1 is an end elevation of an article constructed in accordance with the invention.

Figure 2 is a plan view of the same.

Figure 3 is a perspective view of one of the leaf-engaging members detached.

Figure 4 is a plan view of the binder base alone, portions of the sheet-metal member thereof being broken away.

Figure 5 is a section on line 5—5 of Figure 4.

Figure 6 is a section on line 6—6 of Figure 4.

Figure 7 is a fragmentary section on line 7—7 of Figure 2.

Figure 8 is a fragmentary section on line 8—8 of Figure 7.

Figures 9 and 10 are fragmentary perspective views, showing modifications.

Figure 11 is a view similar to Figure 6, showing another modification.

The same reference characters indicate the same parts in all of the figures.

While the cover may be of any suitable construction, I prefer to make it from a single flexible sheet of leather, paper, cloth, or other suitable material including a back portion 85 12, and side portions 13. To the back is attached by rivets or other suitable fasteners 90 14, an inherently stiff base formed independently of the back. Said base is composed of a relatively thick oblong reinforcing member 15, preferably of press board or binders board, and a sheet metal base member 16, superimposed on one side (hereinafter termed the lower face) of the member 15 and having hooked flanges extending across the longitudinal edges of the reinforcing member and superimposed on the opposite side (hereinafter referred to as the upper face) thereof, each flange including a neck portion 17, and a flat portion 18. The edges of the reinforcing member and the hooked flanges form, along one edge portion of the base, a longitudinal cavity 19, in which the axle portions 20 of the leaf-engaging members described by my former patent, are journaled, and,

along the opposite edge portion of the base, a longitudinal cavity which may be formed in part by notches or recesses 21, in the reinforcing member. The last-mentioned cavity recesses the notched ends of the arched portions 22 of said leaf-engaging members, when the arched portions are turned to engage their notches 23 with the walls of detent-forming orifices 24, as described by said patent.

The sheet-metal base member is provided with guiding slots 25, in one of the hooked flanges, the arched portions 22 extending through and being guided by the walls of said slots. The detent-forming orifices 24 are at the opposite edge portions of the base and preferably formed in the flat portion 18 of one of the hooked flanges, as shown by Figure 6, although they may be formed in the body portion of the reinforcing member, as in the modification shown by Figure 9, and hereinafter described.

The general operation is the same as described in my former patent. When the notched ends of the arched portions 22, enter the detent orifices 24, their entrance is limited by portions of the base member, as indicated by Figures 7 and 8, bottoming the cavity or cavities in which the notched ends are inserted, so that there is a sheet-metal barrier between the notched ends and the cover back, preventing indentation and wear of the back by the notched ends.

It will now be seen that the improved base makes it possible to use flexible leather fabric or paper for the cover, without any stiff back portion being incorporated within the cover.

It will also be seen that the reinforcing member serves a two-fold purpose: First, holding the wire members of the binder in place in the base, one edge of the reinforcing member forming part of the bearing for the axles of the wire portion; and second, supplying necessary support and strength to the sheet-metal base member. This base member is so modified as compared with the form shown by my former patent, that it bottoms the cavities receiving the swinging ends of the arched portions 22, and therefore furnishes in itself the necessary stops for said ends, thereby rendering further reinforcement of the back portion of the cover unnecessary. The result is a stronger, stiffer binding element, complete in itself, adapted to be attached to any form of cover, flexible or otherwise.

The improved base is a further improvement on the former type, in that it presents a flat top surface on which to manipulate paper into or from the arches, as compared with the raised beading of the former type. This flat surface provides better articulation for the locking ends of the arches than does the beaded portion of the former type containing the detent orifices. The sheet metal base mem-

ber is simpler to manufacture, requiring less complicated dies and fewer stamping operations.

The whole device is designed primarily to furnish a binder member complete in itself and of stronger construction than heretofore, which shall permit the use of flexible cover material, without structural reinforcement of the back portion of the cover.

The notches or recesses 21 may be omitted, so that the entire edge forming one side of the cavity receiving the notched ends of the arched portions, is straight and offset inward, as indicated by Figure 11. It will be seen that with the notched form shown by Figures 4, 6, 7 and 8, the edge portions of the reinforcing member, between the notches 21, support the flange containing the detent orifices 24, at opposite sides of said orifices, as indicated by Figure 8, while the form shown by Figure 11 avoids the necessity of exactly positioning the member 15 to cause notches in one of its edges to coincide with the detent orifices 24.

The base member may be inverted from the position shown by Figures 1 to 8, so that the body portion thereof will bear on the outer side of the reinforcing member 15, as in the modification shown by Figure 9, the detent orifices 24 being formed in the body portion, instead of in one of the flanges. In this modification the reinforcing member may be attached to the cover back by fasteners 14, the inverted sheet metal base member being then moved endwise to place on and into engagement with the reinforcing member, the flange portions 18 being interposed between the inner side of the reinforcing member and the cover back.

The body portion of the sheet metal base member may be directly attached to the cover back, as indicated by Figure 10, the reinforcing member being then moved endwise into engagement with the said base member.

I claim:

A temporary binder comprising a base including an elongated reinforcing member of substantially the full length of the base and a transversely bent sheet metal member extending entirely over one face of the reinforcing member, across the adjacent edges of the reinforcing member, out of contact therewith, and onto the opposite face of said reinforcing member throughout the length thereof, whereby the sheet metal member is stiffened throughout its length and provided with interior longitudinally extending cavities, the inner side walls of which are formed by the edges of the reinforcing member, a plurality of slots being provided in the outer side wall and top wall of one of said cavities and corresponding apertures, in substantial transverse alignment with said slots, being provided in the top wall of the other said cavity, a plurality of independent leaf engaging members each extending through one

of said slots and having one end bent laterally into the communicating cavity to form an axle permitting the member to be bodily rocked to move the free end thereof into and from the cooperating aperture in the base, and a cover secured to the base against the opposite face thereof from that from which the leaf engaging members project, said base, reinforcing member and leaf engaging mem-

bers constituting a unitary structure adapted to be employed with a flexible single sheet cover, the base and reinforcing member furnishing the necessary stiffening for the back of the cover.

In testimony whereof I have affixed my signature.

GEORGE H. MOORE.
